RUBIN KARABAN, OF BROOKLYN, NEW YORK.

DISCHARGE TUBE AND CONNECTION.

Application filed April 18, 1925. Serial No. 24,304.

This invention relates to discharge tubes or conductors and means associated therewith for effecting the connection of such tubes or conductors.

5 It is the prime object of the present invention to complete and to therefore obtain perfect results with a means of the character mentioned capable of use in conjunction with a device which is incomplete and crude 10 and which therefore, imperfectly and improperly carries out the result looked for, such as discharging or conducting waste material from one point to another.

Another object of the invention is to provide 15 a device capable of attachment in conjunction with an outlet for conducting waste material and in which the device is capable of ready detachment and re-attachment.

20 Another object of the invention is to produce a discharge tube or conductor embodying a comparatively rigid section and a comparatively flexible section, with attaching means on the rigid section for effecting the 25 connection of the tube or conductor to other devices which are in themselves imperfect and incomplete for carrying out discharging operations.

With the foregoing, other objects of the 30 invention will appear from the embodiment of the invention, which by way of example is described in the following specification, and illustrated in the accompanying drawing, in which:—

35 Figure 1 is a sectional elevation of the device of the present invention shown applied for use in conjunction with a part of a machine which is incomplete, but which is made complete by the application of the 40 device, a portion of the device of the present invention being broken away;

Fig. 2 is a sectional plan view of the device and the device with which it is used.

45 As stated, the device of the present invention is intended for use to complete and to obtain perfect results in conjunction with an incomplete device which does not properly carry out the results looked for. Such incomplete device, for instance, has been 50 found in perforating machines used for perforating leather used in the production of shoes. In carrying out the perforating operations, a punch is employed at the end of a shaft having a hollow section immediately 55 above the punch, into which the punchings

are forced. The hollow section of the shaft has an outlet opening in the side thereof through which the punchings are discharged. At present these punchings fall over parts of the machine, such as the transmission 60 mechanism and other parts, and renders them at times incapable of proper operation. Therefore, such shaft 10, which is mounted for reciprocation in a guide 11, has applied thereto the device 12 of the present invention. 65

The device of the present invention consists of a tube or conductor 13, and attaching means 14. The tube consists of a section 15, which is comparatively rigid and 70 made preferably of metal, and a section 16 connected to the section 15, as at 17, and which is flexible and made preferably of rubber. The attaching means 14 includes portions 18 and 19. The portion 18 carries 75 or has formed thereon, eyes 20, and the portion 19 carries or has formed thereon, a lug 21. The means 14 also includes a clamping member 22 having an eye 23 similar to the eyes 20 and a lug 24 similar to the lug 21. 80 By virtue of the eyes 20 and 23, pivotal connection of the member 22 is effected, as at 20', by the employment of a suitable pin 85 tle extended through the said eyes, as shown most clearly in Fig. 2. Inasmuch as the shaft 10 is cylindrical in cross section, the portions 18 and 19 and the clamping member 22 are capable of conforming to the cross sectional shape of the shaft for the proper application of the device. A screw 90 bolt 25 is employed in conjunction with the lugs 21 and 24, which lugs are apertured to receive the bolt 25, and a nut 26 serves for setting up the clamping action. A holding member 27 is carried by the section 15 and 95 is disposed in contact with the side of the shaft 10 when the device is connected as shown in Fig. 1 to aid in holding the tube or conductor 13 horizontally disposed with respect to the shaft 10. On reference to Fig. 1, 100 it will be apparent that the shaft 10 is hollow, as at 28, and has an outlet 29, and that one end of the tube or conductor 13 is in communication with the interior of the shaft 10 by virtue of the outlet 29 and the connection established. The shaft 10 carries at 105 the lower end thereof a punch 30. In the reciprocation of the shaft 10, the punch 30 operates on material, such as leather, to be perforated, and the punchings are forced 110

into the space 28 and pass from the space 28 into the tube or conductor 13. The constant reciprocation of the shaft 10 plus the crowding force of the incoming punchings 5 and the shifting effect produced by the wall 31 of the shaft, cause the punchings to be discharged through the tube or conductor 13. It will therefore be understood that instead of the punchings dropping out of the 10 outlet 29 on parts of the mechanism of the machine which operate the shaft 10, the punchings will be conducted to a point where they may be received in a suitable receptacle. The use of the flexible section 16 15 permits the proper application of the device in a case where part of the tube has to extend through some relatively fixed part of a machine.

From the foregoing it will be apparent 20 that the device of the present invention has a wide range of application and that the right is reserved to use the same wherever discharging or draining operations are to be carried out in conjunction with parts 25 which are incomplete in the attainment of the result looked for. It will also be ap-

parent that the device may be readily detached to remedy any possible clogging.

What is claimed is:—

1. For use in conjunction with a device 30 having an outlet; a discharge conductor having a flexible portion, and attaching means for operatively positioning the discharge conductor at the outlet, said attaching means comprising coacting clamping portions one of which is hingedly connected at one end of said discharge conductor, and a fastener which coacts with the extremity of said hingedly connected portion and a portion of the discharge conductor for maintaining the coacting relationship of said clamping portions. 35

2. The combination with a punching device including a hollow shaft having an outlet in the side thereof; of a discharge conductor, means for detachably connecting one end of said conductor at said outlet in a substantially horizontal disposition, and means aiding in the maintenance of said end portion of the conductor in the substantially horizontal disposition. 40 45
